CLAIM

The ornamental design for a grounding port connector with through hole, as shown and described.

DESCRIPTION

FIG. 1 is a perspective view of a grounding port connector with through hole showing my new design;

FIG. 2 is a front view thereof;

FIG. 3 is a back view thereof;

FIG. 4 is a side elevation view thereof, the opposite side elevation view is mirror image thereof;

FIG. 5 is a top plan view thereof, bottom plan view is mirror image thereof; and,

FIG. 6 is a perspective back view of a grounding port connector with through hole.

The broken lines shown in FIG. 1 are included for the purpose of illustrating environment and form no part of the claim.
